GRAB BAR OR THE LIKE

Jacob M. Katz, 225 E. 57th St., New York, N.Y. 10022

Filed Aug. 9, 1965, Ser. No. 86,534

Term of patent 7 years

(Cl. D10—8)

FIG.1

FIG.2

FIG. 1 is a front view of a grab bar showing my new design, and

FIG. 2 is a sectional view taken at line 2—2 in FIG. 1. The bar is broken away in part in FIG. 1 to indicate indeterminate length.

I claim:

The ornamental design for a grab bar or the like, substantially as shown and described.
